UNITED STATES PATENT OFFICE.

MACIEJ KORKUS, OF PROVIDENCE, RHODE ISLAND.

LAUNDRY-HANGER.

1,351,335.

Specification of Letters Patent. Patented Aug. 31, 1920.

Application filed October 27, 1919. Serial No. 333,518.

To all whom it may concern:

Be it known that I, MACIEJ KORKUS, a citizen of Poland, residing at Providence, in the county of Providence and State of Rhode Island, have invented certain new and useful Improvements in Laundry-Hangers, of which the following is a specification.

The primary object of the present invention resides in the provision of a laundry hanger wherein there is employed an endless line extending from a point inwardly of a window to an outside support and working over pulleys whereby endless movement thereof may be readily obtained, the slack in the line being controlled by a shifting screw device arranged inwardly of the window.

A further object of the invention is to provide a clothes hanger of the endless type adapted for operation from within a window with a clamping bracket positioned upon a window sill or adjacent part of a building between which the clothes line is adapted to be retained for the suspension of articles thereon to permit the inner end of the rope to be removed from the window opening whereby the window may be closed with the line still maintained in operation.

With the above and other objects in view, the invention consists in the novel form, combination and arrangement of parts herein fully described and shown in the accompanying drawings, wherein like reference characters indicate similar parts throughout the several views.

In the drawing,

Figure 1 is a horizontal sectional view through a portion of a window frame with the present invention in operative position thereon, the clothes line rope being partially broken away,

Fig. 2 is a side elevational view of the rope stretching bracket,

Fig. 3 is a cross sectional view taken on line III—III of Fig. 2 showing the lateral arm for supporting the clothes line roller,

Fig. 4 is a cross sectional view taken on line VI—VI of Fig. 3 showing the bearing for one end of the adjusting screw, and

Fig. 5 is a cross sectional view taken on line V—V of Fig. 2 showing the key-shaped openings in the mounting bracket.

Referring more in detail to the accompanying drawings, there is illustrated a portion of a building A provided with a

window opening B with a window frame C positioned in the opening. The bracket shown more clearly in Figs. 1 and 2 for suspending the inner end of the clothes line is supported on the window frame C and includes a plate or frame 6 substantially triangular in elevation with the base 7 thereof provided with keyhole-shaped slots 8 for detachably mounting on the headed pins 9 secured in the window frame 6 providing a clearance for the screw head.

One longitudinal side of the frame 6 is provided with a coextensive rib 10 constituting a guide for the laterally projecting arm 11, the arm being provided with a slotted portion inclosing the upper edge of the bracket 6 as illustrated in Fig. 3 to permit a free sliding movement of the arm 11 and to prevent swinging movements thereof. The means for adjusting the arm 11 over the bracket 6 comprises a screw 12 threaded through a laterally projecting block 13 upon the frame 6 at the opposite side of the rib 10 while the forward end of the screw 12 extends into the arm 11 and is provided with an annular groove 14 into which the screw 15 carried by the arm projects, thus to permit a free rotary movement of the screw end in the arm and to prevent removal thereof, a washer 16 being provided on the screw exteriorly of the arm 11. The inner end of the screw 12 is provided with an operating handle 17 which when operated, will cause the screw to move relative to the block 13 and carry on the forward end thereof the arm 11 which will in turn slide over the upper end of the bracket 6 as will be clearly obvious.

A clothes line 18 of the endless type travels on a sheave 19 journaled upon the end 20 of the arm 11 and also works upon a sheave 21 journaled in a bracket 22 secured to the support 23 exteriorly of the building. The articles are placed upon the clothes line at points inwardly of the building A and by manipulating the clothes line, the articles are moved outwardly of the window a desired distance. The clothes line is stretched and maintained taut by operation of the screw 12 through the bracket block 13 for shifting the bracket arm 11.

The articles having been suspended upon the line, and it being desired to close the window, the screw 12 is operated to permit the clothes line 18 to be removed from the sheave 19 with both strands of the rope posi-

tioned between the clamped arms 24 carried by the support 25 which is secured to the window sill B at a point adjacent the outer edge, the clamping bars being maintained in closed position by the screw 26 in opposition to the spring 27, it being preferably desirable to form the engaging faces of the clamping arms with interlocking corrugated faces. With the rope 18 clamped between 10 the arms 24, the inner end thereof will be entirely positioned outwardly of the window opening B whereby the window may be closed and if desired, the frame 6 removed from the window frame C by disconnecting 15 the rear section thereof from the pins 9. Similarly, the clothes are removed from the line by attaching the inner end of the rope to the sheave 19 and stretching the rope by the screw 12 and then moving the rope over 20 the sheaves 19 and 21 to bring the articles upon the clothes line 18 into the reach of the operator.

While there is herein shown and described what is believed to be the preferred embodiment of the invention, it is nevertheless to be 25 understood that minor changes may be made in the form, combination and arrangement of parts without departing from the spirit and scope of the invention as claimed.

What is claimed as new is:—

A support for endless clothes lines including a frame, means to detachably rigidly connect said frame to the inner side of a window casing so as to project inwardly from the latter, a laterally extending arm 35 slidable on said frame, a pulley carried by said arm over which the endless clothes line is adapted to travel, a block carried by the inner end of said frame, a screw threaded through said block and rotatably connected 40 at its outer end to said arm, and means for operating said screw.

In testimony whereof I affix my signature.
MACIEJ KORKUS.
